UNITED STATES PATENT OFFICE

112,475

DESIGN FOR A DRESS

Edna Breer, New York, N. Y.

Application November 8, 1938, Serial No. 80,948

Term of patent 3½ years

To all whom it may concern:

Be it known that I, Edna Breer, a citizen of the United States, and a resident of the city of New York, in the county of New York and State of New York, have invented a new, original, and ornamental Design for a Dress, of which the following is a specification, reference being had to the accompanying drawing constituting a part thereof:

Fig. 1 is a front view of the dress showing my new design.

Fig. 2 is a rear view of the dress shown in Fig. 1.

The characteristic features of my design reside in the puffed designs on the sleeves, shoulders and back in combination with the dress as shown.

I claim:

The ornamental design for a dress, substantially as shown and described.

EDNA BREER.
